TURRET-TYPE TOOL POST

Gordon J. Benes, Chicago, Ill., assignor to
Enco Mfg. Co., Chicago, Ill.

Application February 14, 1944, Serial No. 522,334

3 Claims. (Cl. 29—48)

1

My invention relates to turret-type toolposts as used on bench lathes, engine lathes, turret lathes and screw machines, and my main object is to provide a tool-supporting turret which is easily adjustable to train or set tools in desired positions or directions.

A further object of the invention is to provide a turret of the above character which has self-finding and positively-engageable locating means for the tool holding element.

Another object of the invention is to provide a simple, handy and efficient control for securing or releasing the tool holding element.

An important object of the invention is to design the improved turret with few parts which are rugged, durable and compactly assembled.

With the above objects in view and any others which may suggest themselves from the description to follow, a better understanding of the invention may be had by reference to the accompanying drawing, in which—

Fig. 1 is a schematic plan view of a lathe bed and compound, showing the location of the improved turret;

Fig. 2 is an enlarged plan view of the turret alone in the idle or released position;

Fig. 3 is a section on the line 3—3 of Fig. 2, showing the application of the turret to the lathe compound; and

Fig. 4 is a cross-section of the turret illustrated in Fig. 3, showing it in the fixed or engaging position.

Referring specifically to the drawing, 10 denotes the bed and 11 the tool compound of a typical lathe or similar machine. The turret is mounted on the compound, and may be secured to the same in any suitable manner. One method of securing the turret is indicated in Figs. 1 and 3, as a matter of example. Thus, the compound is made with an inverted-T cross-slot into whose entrance a tongue 14 depending from the turret base 15 projects. A plate 16 lies in the head portion of the slot 13 and is tapped to receive bolts 17 from the top of the turret base 15, so that to all intents and purposes the turret base may be considered as rigidly fixed to or forming a part of the compound.

The turret base 15 is circular in contour, and is designed to receive a square, overlapping headpiece 18 from above. As many as four tools (not shown) may thus be mounted horizontally in the sides of the turret, receptacles 19 being formed in the sides of the headpiece 18 for this purpose. The headpiece is vertically tapped in several places over the receptacles 19 to receive socket-

2

screws 20 for clamping the tools deposited therein.

The base and headpiece of the turret are aligned vertically by a center post 21 slidable in matching bores 22 and 23 made in the respective parts. The bore 22 is chambered at the bottom, as indicated at 24, to seat the head 25 of the center post; and the latter rises from the headpiece reduced in thickness by flat formations 26 on opposite sides.

Fig. 3 shows the headpiece in a floating position over the base; and the headpiece is intended to be rotatable about or with the center post 21 relative to the base when in this position, a circular bottom recess 27 in the headpiece receiving a similarly-formed projection 28 of the base for rotary guidance or alignment. The floating position of the headpiece is maintained by a series of steel balls 29 and supporting springs between the headpiece and the base. Thus, the bottom of the headpiece is made with a shallow ball seat 30 opposite the middle region of each side; and with the headpiece and base in the matching relation illustrated, a set of recesses 31 are made in the base opposite the ball seats 30. The recesses 31 are continued with center wells 32 in which vertical coil springs 33 are deposited. The steel balls 29 seat in the headpiece seats 30; and the normal length of the springs 33 causes them to support the steel balls partly in the recesses 31.

The fit of the balls 29 between the headpiece and base as described serves to locate or tentatively fix the position of the headpiece; but it may be rotated relative to the base by tripping the balls 29 and riding on them until they seat in the next or any subsequent position of the seats 30, the springs 33 yielding to the momentary depressing influence of the headpiece on the balls 29. The arrangement of these thus serves as a self-locating feature for the headpiece, to set the same at every quarter turn. While the locating feature employs four stations or locations in the present embodiment, it may be desirable to have more locations for the setting of tools at oblique angles, in which eight or even twelve stopping or locating seats could be formed in the headpiece.

When the turret headpiece has been stopped or set in a desired position with reference to the base, it must be firmly secured in that position. For this purpose an arm 35 having a handknob 36 is employed. The base 37 of the arm is bifurcated, as indicated at 38, to straddle the reduced portion 26 of the center post 21, receiving a tapered cross-pin 39 to make a pivotal joint with the same.

When the turret headpiece is in the floating

3

position indicated in Figs. 1 to 3, the arm 35 lies on its side, resting on a conical ring 40 which seats in a similarly-formed recess 41 in the top of the headpiece. The forks 38 of the arm 35 are rounded as climbing cams 42, which are designed to bear progressively on the ring 40 when the arm 35 is swung in an upward direction. The pressure of the cams 42 is transmitted to the headpiece and on the descent thereof to the series of balls 29 as the arm 35 approaches the vertical position indicated in Fig. 4. Now the balls 29 seat in the bottoms of the recesses 31 to the extent of supporting the headpiece in slightly spaced relation to the base, as shown in the figure last referred to. It is now evident that the pressure of the arm 35 locks the headpiece and base into one non-separable unit. In this respect, the cams 42 may be designed with a slight reduction beyond the point of greatest pressure as the arm assumes the vertical position, so that the arm may assume a resistance against accidental return. It is understood that the conical ring 40 is in the nature of a washer or facing which may be turned or even replaced in case of undue wear from the cams 42.

While the control arm 35 is primarily employed to secure or release the headpiece of the turret, it is also employed to rotate the headpiece to the desired stop. For this purpose the headpiece receives an equidistant series of vertical pins 45, whose heads 46 project above the top of the headpiece to a limited extent. The base 37 of the arm 35—when lying on its side—receives a similar pin 47 with its head 48 projecting downwardly, the location of the pin 47 being such that the projected portion of its head will strike the corresponding portion of the first pin 45 in its path when the arm 35 is swung in a horizontal plane to turn with the center post 21. The headpiece of the turret may thus be rotated from any point where the horizontally positioned arm 35 may be located. The meeting faces of the pin heads 46 and 48 are preferably chamfered flat, as indicated at 49, for better contacting engagement. Fig. 2 shows that the series of pins 45 is staggered to some extent in respect to the ball recesses 30 in order to definitely clear the latter when the pin holes are drilled, since it is immaterial at what point of horizontal sweep the control arm 35 stops or acts, as long as it retains its central clamping influence and finds a pin head 46 to engage on a partial turn when the headpiece is to be rotated.

It will be evident that I have provided a tool-holding turret which employs the efficient principle of a cam arm to clamp it tight. This it couples with the floating support of the headpiece which incorporates the self-locating feature. The latter is distributed to afford uniformity both in the floating support and the clamping of the turret to serve as a rigid unit after the tool-holding headpiece has been turned to the desired position. The internal matching elements between the headpiece and the base insure vertical and rotary alinement between these members, while the overhanging marginal flange 43 of the headpiece forms a closure against the entrance of metal shavings or dust into the space occupied by the balls 29 and springs 32. The simple control arm is maneuverable with one hand to either turn or clamp the headpiece, making it easy to operate the turret. Finally, the latter incorporates the above described features in a sturdy and compact unit which is formed to facilitate the

smooth and efficient action of the mechanism between the headpiece and the base.

While I have described the invention along specific lines, various minor changes or refinements may be made therein without departing from its principle, and I desire to consider such changes and refinements as coming within the scope and spirit of the appended claims.

I claim:

1. A tool-holding turret for lathes and like machines comprising a base attachable on the tool support of the machine, a post rising from the center of the base, a tool-holding headpiece mounted on the base, said headpiece being vertically perforated for the passage and upward projection of said post and rotatable about the same, an arm carried by the projecting part of the post in a horizontal position and having means to clamp the headpiece to the base when the arm is moved to vertical position, other means in part carried by the arm and in part by the headpiece to rotate the same when the arm is turned in a substantially horizontal plane about the post, said arm being pivoted to said projecting part by straddling the same, said clamping means being cams formed endwise on the straddling portions, the headpiece having a depression around the post defined by an inclined annular wall, and a removable wear-absorbing conical ring on the headpiece around the post and seating in said depression, said cams bearing down on the ring when the arm is moved as stated to depress the headpiece.

2. A tool-holding turret for lathes and like machines comprising a base attachable on the tool support of the machine, a post rising from the center of the base, the latter having a set of spaced recesses in the upper portion thereof with each recess seating a spring-pressed ball, a tool-holding headpiece including a bottom surface having a series of shallow recesses for receiving said balls and resting on the upper surface of said base, said headpiece being vertically perforated for the passage and upward projection of said post and rotatable about the same, an arm carried by the projecting part of the post in a horizontal position, means adapted to be pressed by the arm to clamp the headpiece to the base when the arm is moved to vertical position, and spaced means projecting from the upper surface of the headpiece in staggered relation to said ball recesses engageable by said arm to rotate the headpiece when the arm is turned in a substantially horizontal plane about the post, said means to clamp the headpiece to the base including a tapered seat formed centrally in the top of the headpiece, and a wear-absorbing ring seated therein engageable by said arm.

3. A tool-holding turret for lathes and like machines comprising a base attachable on the tool support of the machine, a post rising from the center of the base, the latter having a set of spaced recesses in the upper portion thereof with each recess seating a spring-pressed ball, a tool-holding headpiece including a bottom surface having a series of shallow recesses for receiving said balls and resting on the upper surface of said base, said headpiece being vertically perforated for the passage and upward projection of said post and rotatable about the same, an arm carried by the projecting part of the post in a horizontal position, means adapted to be pressed by the arm to clamp the headpiece to the base when the arm is moved to vertical position, and spaced means projecting from the upper surface

of the headpiece in staggered relation to said ball recesses engageable by said arm to rotate the headpiece when the arm is turned in a substantially horizontal plane about the post, said means to clamp the headpiece to the base including a **5** conical seat formed centrally in the top of the headpiece, and a removable wear-absorbing conical ring surrounding said post mounted within said seat and engageable by said arm.
